UNITED STATES PATENT OFFICE.

THOMAS MIDGLEY, SR., AND THOMAS MIDGLEY, JR., OF LANCASTER, OHIO.

COLLAPSIBLE CORE.

1,188,004.

Specification of Letters Patent. Patented June 20, 1916.

Application filed January 24, 1916. Serial No. 73,772.

To all whom it may concern:

Be it known that we, THOMAS MIDGLEY, Sr., and THOMAS MIDGLEY, Jr., citizens of the United States, residing at Lancaster, in the county of Fairfield and State of Ohio, have invented certain new and useful Improvements in Collapsible Cores, of which the following is a specification.

This invention relates to collapsible cores 10 designed for use in connection with the manufacture of pneumatic tire casings and particularly in connection with inextensible edged casings.

The principal object of our invention 15 resides in the peculiar construction of joint between the various sections forming the core annulus, whereby the circumferential strain is relieved to a marked extent and also wherein the lateral or sidewise play of 20 the various sections is eliminated.

A further object of our invention resides in the means for holding the core sections in assembled relation.

The preferred embodiment of our invention 25 is shown in the accompanying sheet of drawings, in which similar characters of reference designate corresponding parts, and in which:

Figure 1 is a side view partially in section of a segment of core, Fig. 2 is a top plan view of the segment shown in Fig. 1, and, Fig. 3 is a section taken on line 3—3 of Fig. 1.

It is to be understood that the present core 30 is composed of a plurality of sections 1 and 2 sufficient in number to form an annulus, over which the tire may be formed. The abutting ends of the present sections 1 and 2, as shown, are of general Z-shape, the leg 35 portion being designated generally by the reference numerals 3 and 4 and the portion between the legs, or, as we have termed it, the intermediate portion, is designated generally by the reference numeral 5. These 40 abutting ends are preferably faced with face plates such as shown at 6, and this facing may be made in any manner desired. In the present embodiment, we have shown four plates 6 arranged in two sets of two 45 each, the outside plates of each set being stamped out as is shown at 7 and the two plates forming each set being riveted together, so that the facing plates may be attached to the various core segments during 50 the process of casting, by placing these plates when in their assembled relation, in

the mold imprint. This method of constructing a collapsible core is shown and described in Patent No. 1157118 issued October 19, 1915, jointly to us. The specific 60 construction of facing plates is immaterial to the present invention, however. It is desirable that these facing plates be provided with concaved portions 8, so that a tongue and groove structure is provided for the 65 ends of abutting sections to prevent sidewise or lateral play of these sections. Further, the intermediate portion 5 of these plates is also preferably shaped to present an offset portion 9, the offset in the present 70 case being in a direction toward the outer periphery of the annulus as a whole. This latter construction is provided to relieve the circumferential strain when pressure is applied to the sides of the formed tire casing 75 before and during the time it is cured. Where this pressure is applied directly to the sides of the tire and consequently to the sides of the core, the natural tendency is for 80 this annulus to increase its diameter and to do this there must be a separation between joints or between the abutting ends of the various core sections. If this slight expansion is permitted, there is, of course, a 85 groove formed on the interior of the tire casing, which is undesirable, and to avoid this and to also avoid shearing of the bolt structure to be presently described, we have provided the offset portion 9. It will be 90 noted that this offset or hook shaped portion interlocks the core sections in a circumferential direction and consequently the circumferential strain between the sections 95 is overcome.

In order to hold the various core sections 100 in their assembled relation, we have provided a bolt structure designed to pass through the intermediate portions 5 of the abutting core segments, this bolt structure comprising a bushing 10 having an enlarged 105 head 11 and extending into the core section 2. The interior of this bushing is threaded to receive the screw 12 which screw passes radially through the end of the core section 1. When the cores have been originally 110 formed, the various sections are assembled and a hole the size of the screw 12, is drilled through both abutting ends. The end of the section 2 is then counterbored to receive the shank portion of the bushing 10 and this is then counterbored to receive the head portion 11 of the bushing. This bushing is

made to have a driving fit with the core section 2 and in this manner the two ends must properly aline. The bushing 10 is itself provided in case the threads operating 5 in connection with the screw 12 should be stripped. If these threads were made directly into the core body, it would, of course, be necessary to discard the entire core, but where these threads are stripped from the 10 bushing 10, it is only necessary to remove this bushing and to replace it with another one:

From the foregoing description, it will be apparent that we have provided a type of 15 core which may be made at a considerably reduced cost. This is especially true when the facing plates 6 are attached to the core segments, after the manner illustrated in the patent referred to above, in which case the 20 expense of properly shaping these plates is the same for all cases, with possibly the exception of the initial cost of the dies. It will be seen that we have so shaped the abutting ends of these sections that they 25 interlock to prevent lateral or sidewise play between sections and also interlock or engage each other to relieve the circumferential strain caused by the pressure applied to the sides of the core and tire casing during its manufacture. In addition, the manner 30 of holding these various core segments together is very simple and also very efficient, it being possible to knock down an entire core by the removal of the screws 35 12 only.

What we claim is:

1. A collapsible core comprising a plurality of core sections to form an annulus and means for holding said sections together, the abutting ends of said sections 40 being shaped to interlock to prevent sidewise play and also shaped to present an offset portion to relieve circumferential strain.

45 2. A collapsible core comprising a plurality of core sections to form an annulus, a bolt structure passing through the ends of

abutting sections to hold them together, the abutting ends of said sections being shaped to interlock to prevent sidewise play and 50 also shaped to present an offset portion to relieve circumferential strain.

3. A collapsible core comprising a plurality of core sections to form an annulus, the abutting ends of said members being of 55 general Z-shape, and a bolt structure passing through the intermediate portion of said Z-shaped ends.

4. A collapsible core comprising a plurality of core sections to form an annulus, the abutting ends of said members being of 60 general Z-shape, one pair of registering legs at each joint being shaped to interlock to prevent sidewise movement and the intermediate portion of each joint being shaped 65 to present an offset to relieve circumferential strain, and means for holding said sections in their assembled relation.

5. A collapsible core comprising a plurality of core sections to form an annulus, 70 the abutting ends of said members being of general Z-shape, one pair of registering legs at each joint being shaped to interlock to prevent sidewise movement and the intermediate portion of each joint being shaped 75 to present an offset to relieve circumferential strain, and a bolt structure passing through the intermediate portions of said Z-shaped ends.

6. A core comprising a plurality of core 80 sections to form an annulus, the abutting ends of said sections being shaped to permit the removal of a core section inwardly, a threaded bushing located in the end of one section, and a screw passing through the end 85 of the abutting section and adapted to be threaded into said bushing.

In testimony whereof we affix our signatures in presence of two witnesses:

THOMAS MIDGLEY, SR.
THOMAS MIDGLEY, JR.
